US0D1105085S

(12) **United States Design Patent** (10) **Patent No.:** **US D1,105,085 S**
(45) **Date of Patent:** **** Dec. 9, 2025**

(54) **COMPUTER CASING**

(71) Applicant: **Lenovo (Beijing) Limited**, Beijing (CN)

(72) Inventor: **Chien Yu Hsieh**, Beijing (CN)

(73) Assignee: **Lenovo (Beijing) Limited**, Beijing (CN)

(**) Term: **15 Years**

(21) Appl. No.: **35/522,859**

(22) Filed: **Jun. 19, 2024**

(80) **Hague Agreement Data**

Int. Filing Date: **Jun. 19, 2024**

Int. Reg. No.: **DM/241577**

Int. Reg. Date: **Jun. 19, 2024**

Int. Reg. Pub. Date: **Nov. 8, 2024**

(30) **Foreign Application Priority Data**

Dec. 20, 2023 (CN) 202330839579.0

(57) **CLAIM**

The ornamental design for a computer casing as shown and described.

DESCRIPTION

1. Computer casing
2. Computer casing
- 1.1 : Front
- 1.2 : Back
- 1.3 : Left
- 1.4 : Right
- 1.5 : Top
- 1.6 : Bottom
- 1.7 : Front, left, top side perspective view
- 1.8 : Front, right, bottom side perspective view
- 2.1 : Front
- 2.2 : Back
- 2.3 : Left
- 2.4 : Right
- 2.5 : Top
- 2.6 : Bottom
- 2.7 : Front, left, top side perspective view
- 2.8 : Front, right, bottom side perspective view

The broken lines shown in the drawings illustrate portions of the computer casing that form no part of the claimed design.

1 Claim, 16 Drawing Sheets
